Inventor
John J. O'Reilly,
By his Attorney C. P. Goepel.

UNITED STATES PATENT OFFICE.

JOHN J. O'REILLY, OF BROOKLYN, NEW YORK.

PIPE-BENDING DEVICE.

1,420,336.

Specification of Letters Patent. Patented June 20, 1922.

Application filed August 26, 1919. Serial No. 319,915.

To all whom it may concern:

Be it known that I, JOHN J. O'REILLY, a citizen of the United States of America, residing at the borough of Brooklyn, county 5 of Kings, city and State of New York, have invented certain new and useful Improvements in Pipe-Bending Devices, of which the following is a specification.

This invention relates to pipe bending devices and has for its primary object to provide a very simple and serviceable means whereby pipes or conduits, such as are used in the installation of electric circuits during the erection of a building, may be easily and 15 quickly bent in order to enable the pipe or conduit to be properly laid or extended in the desired direction.

It is a more particular object of my invention to provide a pipe bending device in 20 the form of a metal block or casting having means whereby the device may be readily applied to and securely retained in position for use upon a beam flange, plank or other relatively fixed support, the casting being 25 also formed with recesses to receive pipes of various diameters.

My invention also contemplates the provision of a pipe bending device, as above characterized, which may be manufactured and 30 sold at relatively small cost, and can be easily and quickly arranged in position for use or removed and readily transported from place to place.

With the above and other objects in view, 35 the invention consists in the improved pipe bending device above referred to and in the form, construction and relative arrangement of its several parts, as will be hereinafter more fully described, illustrated in the accompanying drawing, and subsequently incorporated in the subjoined claims.

In the drawing wherein I have shown several practical embodiments of my invention:

Fig. 1 is a side elevation showing the pipe bending device in the form of a single metal casting operatively arranged upon a beam flange;

Fig. 2 is an end elevation showing a reducing member associated with the bending device, and illustrating in dotted lines pipes of different sizes arranged in position to be bent;

Fig. 3 is a side elevation illustrating another means for securing the bending device in position for use;

Fig. 4 is an end elevation illustrating an

alternative embodiment of the invention; and

Fig. 5 is an elevation of a further modification.

Referring in detail to the drawing, and more particularly to Figs. 1 and 2 thereof, 60 5 designates the body of the pipe bending device, which, as herein shown, is in the form of a single metal block or casting, preferably, though not necessarily, of rectangular shape. This metal casting 5 is provided on one side with a longitudinally extending channel or recess 6, the inner portion of which is reduced in width as at 7, by the 65 longitudinally extending shoulder 8 which, in the illustrated construction, projects downwardly from the top wall of the recess 6. Thus there is provided two longitudinal channels or recesses opening upon the opposite ends of the block or casting which are 70 adapted to receive pipes of relatively different diameters as indicated at P.

On the opposite side face of the block or casting 5, a relatively wide longitudinally 75 extending channel 9 is formed for the purpose of receiving pipes of larger sizes than those indicated at P. A reducing member 80 10, in the form of an angle bar, may be inserted into this channel, as shown in Fig. 2, 85 so as to reduce the area thereof in accordance with the diameter of the pipe to be bent. It will be understood that several of these reducing members may be provided and assembled together within the channel 90 9 when a further reduction in the area of said channel is necessary.

In the lower portion of the block or casting 5, below the channels 6 and 9, a groove or recess 11 is formed and extends in a direction at right angles to said channels. This groove is adapted to receive the flange F of a beam B, or any other suitable fixed or stationary object. The groove or recess 11 is of sufficient depth so that the lower portion 95 12 of the block or casting will have an extensive bearing surface against the underside of the flange F and thus prevent tilting or rocking movement of the device upon the beam. Having mounted or arranged the bending device upon the fixed support in the manner shown in Fig. 1 the pipe may be 100 readily engaged in any one of the recesses or channels 6, 7 or 9, and bent over the end face of the block or casting in the desired 105 manner.

In Fig. 3 of the drawing, I have indicated

another means for securing the bending block in a fixed position. This means consists in the screw 13 which has threaded engagement in the block or casting 5 and is 5 adapted to be adjusted through an opening bored in a plank F' engaged in the groove or recess 11 of the bending block. It is to be understood, however, that when the holding screw 13 is employed, if desired, the 10 lower flange 12 of the bending block may be eliminated or the screw may be adjusted through an opening in said flange and engaged in the opening of the board or plank F' when arranged beneath the base flange of 15 the block.

In Fig. 4 of the drawing I have disclosed an alternative construction of the device wherein the bending block consists of the upper and lower sections 14 and 15 respectively, said upper section having a reduced portion 16 and the lower section being provided with a central upwardly extending portion 17, the upper faces of its lower section at opposite sides of the extension 17 25 being disposed in different horizontal planes. A sleeve 18 extends upwardly from the central extension 17 of the lower block section 15 and in this sleeve a clamping screw 19 has threaded engagement, the lower end of said screw being threaded in the block section 15 as indicated at 20. The sleeve 18 is provided in its outer surface with a keyway 21 to receive a key on the plate 22. This plate is provided at diametrically opposite points 30 with lugs 23 to seat in recesses formed in the upper surface of the block section 14. Thus this block section is securely held against turning movement upon the sleeve 18. By means of the screw 19, the block sections 40 may be mounted upon the beam, board or other fixed object. The upper block section 14 may then be adjusted upon the sleeve 18 relative to the lower section 15 so as to provide channels or recesses at opposite sides 45 of the desired width. Thus it will be apparent that if the position of the section 14 as seen in Fig. 4 with respect to the section 15 is reversed, a relatively wide channel will be provided on one side of the device while 50 at the opposite side thereof a very narrow channel will be provided. After adjusting the section 14 it is securely held against turning movement by means of the locking plate 22. In this manner I provide a device which may be easily and quickly adjusted for the purpose of receiving pipes of many different sizes.

In Fig. 5 of the drawing, I have disclosed still another form of the invention wherein 60 the bending device is arranged upon one flange of the beam B as in Fig. 1, and upon the other flange of this beam, a clamping member 24 is positioned. A screw 25 has a section provided with left hand screw threads 26 engaged in the clamping member

24, while the end of the screw is provided with right hand threads 27, which are engaged in the bending block 5. It will thus be apparent that by adjusting this screw, the block 5 and member 24 may be moved towards each other and securely clamped upon the opposite flanges of the beam B, and by reversing the rotation of the screw the parts may be easily and quickly disengaged from said flanges and the device removed. 75

From the foregoing description considered in connection with the accompanying drawing, the construction and manner of use of the several illustrated embodiments of the invention will be clearly and fully 80 understood. In view of the very simple construction of the device it will be apparent that my invention may be manufactured and sold at comparatively small cost, and as it may be easily transported from place to 85 place, the device is of great utility in the laying of lead pipe or conduits during the erection of buildings for the purpose of receiving electrical circuit wires. I have herein disclosed several forms of my improved pipe bending device, which I consider very practical for the intended purpose. Nevertheless it is to be understood that the invention may also be exemplified in numerous other alternative constructions, 95 and I therefore reserve the privilege of adopting all such legitimate changes as may be fairly embodied within the spirit and scope of the invention as claimed. 100

I claim:

1. A pipe bending device comprising a block having a base and an enlarged head, the intermediate portion of the block between the base and head being cut out at opposite sides to provide various sized recesses in which to receive and hold pipes of different diameters, said block having at its intermediate central portion a web connecting the base and head and separating the cut-away portions at opposite sides of the intermediate portion and taking up the strain centrally of the block. 105

2. A pipe bending device comprising a block having an enlarged base adapted to seat upon a suitable support and provided with a head above the base and with an intermediate portion cut-away through opposite sides of the block leaving a central web connecting the base and head, the cut-away portion at one side of the web being stepped and having an over-hanging portion in one piece with the web and head to reinforce the same, and a filler block adapted to be fitted in the opposite cut-away portion and having a leg lying against the web and reinforcing the same. 110

3. A pipe bending device comprising a block having a base and head with the intermediate portion cut-away at both sides of the block leaving a web therebetween con- 125

necting the head and base, said head provided with faces at different elevations relatively to the base and being rotatable to bring either face above opposite cut-away portions.

4. A pipe bending device comprising a block having a base adapted to seat upon a suitable support and a head above the base, the intermediate portion of the block being 10 cut-away at opposite sides leaving a web between the cut-away portions, the upper faces of the base being stepped, the lower faces of the head being at different elevations at opposite sides thereof, said head being rotatable relatively to the base, and means to 15 secure the head in adjusted position.

5. A pipe bending device comprising a

block having a base and head with a connecting web centrally therebetween and with cut-away portions at opposite sides of the 20 block, the upper face of the base at one side of the web being higher than the face at the other side of said web, one lower face of the head being higher than the other face of the head at the opposite side of the web, 25 said head being rotatable to bring either face thereof above the other face of the base, and means for holding said head in adjusted position and also for securing the base on a support.

In testimony that I claim the foregoing as my invention, I have signed my name hereunder.

JOHN J. O'REILLY.
